Primary Examiner — Susan E Krakower(74) *Attorney, Agent, or Firm* — Woodard Emhardt Moriarty McNett & Henry LLP(57) **CLAIM**

The ornamental design for a exercise slide board, as shown and described.

DESCRIPTION

FIG. 1 is a perspective view of an exercise slide board showing my design;

FIG. 2 is a front view thereof;

FIG. 3 is a rear view thereof;

FIG. 4 is a right side view thereof;

FIG. 5 is a left side view thereof;

FIG. 6 is a top plan view thereof; and,

FIG. 7 is a bottom plan view thereof.

The broken lines depict environmental subject matter only and form no part of the claimed design.
